UNIVERSAL RESISTANCE CAPACITANCE FILTER

Ellison S. Purington, Gloucester, Mass., assignor, by mesne assignments, to Radio Corporation of America, New York, N. Y., a corporation of Delaware

Application August 26, 1942, Serial No. 456,286

7 Claims. (Cl. 178—44)

This invention relates to a network of resistors and capacitors which may be used for frequency discrimination purposes. It is especially useful in frequency ranges where inductance elements are not highly practicable, as, for example, in low audio or sub-audio ranges. By properly chosen design constants, the network may have the properties of a low-pass, a high-pass, a band-pass or a band elimination filter, as may be desired.

In the drawing, Figure 1 shows the general nature of the filter network according to the invention, and Figures 2 and 3 illustrate curves which will serve to explain the performance of the filter network of Figure 1 under certain conditions.

The circuit of Figure 1 comprises a frequency discriminating network with structural symmetry which is set up between two equal terminating resistors R , one of which, the sending termination, contains a source of alternating current energy E . The current i_r in the other termination, the receiving termination, is a function of the magnitude and the frequency of the source. The frequency discriminating network comprises the condensers C_3 , C_1 , C_1 and C_3 connected in series between the terminating resistors R and R , the shunt condensers C_2 and C_2 , the series connected resistors R_1 , R_1 which shunt the condensers C_1 , C_1 , the shunt condenser $2C_1$ having one terminal connected to the common terminal of resistors R_1 , R_1 and the shunt resistor

$$\frac{R_1}{2}$$

having one terminal connected to the common terminal of the condensers C_1 , C_1 . The restriction of symmetry is for the purpose of making the performance a matter of exact computation without excessive difficulty, and it will be understood that the performance will not change abruptly if the conditions of exact symmetry are not met. There are five independently choosable elements, R , R_1 , C_1 , C_2 , C_3 , and the general performance information covers all possible combinations of choices.

The filtering performance is most conveniently expressed by the insertion ratio, that is, the ratio of the current, $E/2R$, which would flow in the output arm if the filtering network were absent and E , R and R directly in series, to the actual current i_r flowing with the filtering network present. Using vector notation

$$\text{insertion ratio} = \frac{E/2R}{i_r} = (M + jN)$$

where M and N are functions of frequency and the relative proportions of the various elements. From M and N , the performance as to effect of the filter network upon the magnitude and upon the phase of the output current is given by

$$\text{insertion loss (db)} = 10 \log_{10} (M^2 + N^2)$$

$$\text{insertion } \phi \text{ lag} = \tan^{-1} \left(\frac{N}{\sqrt{M}} \right)$$

10 The insertion loss effect is of primary importance in describing the properties of the filter network, but the phase shifting effect is sometimes required.

15 In some cases, it may be desirable to know the transmission ratio T instead of the insertion ratio, that is, the ratio of the voltage e_r across the receiving termination to the driving voltage E . This is deducible from M and N by the relations

$$T = \frac{e_r}{E} = \frac{1}{2(M + jN)} = \left(\frac{M}{2(M^2 + N^2)} \right) - j \left(\frac{N}{2(M^2 + N^2)} \right)$$

Because the performance is on a relative basis, the performance is independent of the magnitude of E , but depends only upon the frequency. Further the insertion ratio is not modified if the value of each resistor in ohms is multiplied by a given factor, and the value of each capacitor in farads divided by the same factor, since this does not modify the ratios of the impedances of the elements. That is, although there are five independently choosable elements, there are only a fourfold infinitude of performance relations possible between the insertion ratio and the frequency of the source.

The number of infinitude of performance curves is further reduced by putting frequency as well as transmission on a relative basis. That is, we can set up as a reference frequency F_0 , the frequency for which a resistor element of the system has the same numerical impedance as a capacitor element. Preferably F_0 should represent some physically describable phenomenon.

45 For the present purposes, F_0 is chosen as the frequency for which the capacitor C_1 has the same numerical impedance as resistor R_1 . That is, for a given choice of C_1 and R_1 , the reference frequency is determinable by $F_0 = 159200/C_1R_1$,

50 where C_1 is in microfarads, R_1 in ohms, and F_0 in cycles per second. For simplicity, the performance can be expressed not in terms of frequency, but in terms of the reduced or relative frequency, which is the ratio of any frequency f to the reference frequency F_0 . This for simplic-

ity may be termed x , the main independent variable in expressing the performance.

By thus placing the transmission on a relative basis, and also the frequency on a relative basis, the performance of insertion effect as a function of the relative frequency is expressible by a three fold infinitude of curves. That is, the insertion effect is a function of x and of three secondary independent variables or parameters, expressing the ratios of impedances. These parameters will be as follows:

Parameter h (height) is the ratio of R_1 to R , that is $h=R_1/R$;

Parameter s (series) is the ratio of C_1 to C_3 , that is $s=C_1/C_3$;

Parameter p (parallel) is the ratio of C_2 to C_1 , that is, $p=C_2/C_1$.

The parameter h is an impedance level parameter. As h is changed, the impedances of all elements of the filtering network are changed with respect to the terminations, without changing the ratios of the impedances of the elements without the filter itself. Parameter s expresses the series condenser effect in blocking the passage of low frequency currents, and this effect is zero for $s=0$, making C_3 infinite. Similarly p expresses the parallel condenser effect in preventing the passage of high frequency currents, and the effect is made zero for $p=0$, making C_2 zero. For both s and p zero, the network comprises solely the central elements R_1 , C_1 , $R_1/2$ and $2C_1$. With h , s and p all positive quantities, the insertion ratio function M and N depend solely upon the main independent variable x , and the secondary independent variables h , s and p . Without going into the details of the method of solution, it will be found that M and N are computable from the equation below:

$$M = \frac{(Px^2 - Q)}{(x^2 - 1)}; N = \frac{(Ux^3 - Vx + W/x)}{(x^2 - 1)}$$

$$P = [1 + 2p(1 + s + sp)] + h^{-1}[2 + 4p + p^2]$$

$$Q = [1 + 4s + 2sp] + h[2s^2 + (1 + sp)(1 + 4s + sp)]$$

$$U = h^{-1}[p(1 + p)]$$

$$V = h^{-1}[2 + p] + [4 + 4s + 2p + 8sp + 2sp^2] + h[(1 + sp)(1 + s + sp)]$$

$$W = h[s(1 + 2s + sp)]$$

The quantities P , Q , U , V , W assume numerical values when parameters h , s and p are specified. These numerical values are then inserted in the equations for M and N to make the insertion ratio a function of x corresponding to the particular values of h , s , p chosen. This is simpler than having M and N expressed in terms of one long equation involving x , h , s and p .

In using these equations for design purposes, it is contemplated that performance curves will be computed say of insertion loss as a function of x for various combinations of h , s and p . By a method of trial and adjustment, a combination of h , s and p will be found that best approximates the desired performance curve shape. The terminal resistances R being known, and it being established from the chosen curve as to what value should be assigned to F_0 , the various elements can be computed by the following formulae:

$$R_1 = hR; C_1 = 159200/R_1F_0; C_2 = pC_1; C_3 = C_1/s$$

For purpose of illustration, in Figure 2 are shown curves of insertion loss in decibels under the special condition of $p=s=0$, so that C_2 and C_3 are not required, one being zero and the other

infinite. The parameter h is assigned three different values. For

$$h = \sqrt{2}$$

the insertion loss function is the simplest possible, being the same for x as for $1/x$. This arrangement is suitable for band elimination purposes. Theoretically the loss is infinite at $x=1$. It will be understood that the loss in the vicinity of $x=1$ can be made finite if desired by causing the various elements of the filter to be inexactly chosen. The dotted line in the curve is for the purpose of tying the two portions of the curve together. But with parameter h chosen large, say $h=10$ as illustrated, the system has the properties of a high-pass filter, with high loss for low values of x , and especially high loss near $x=1$. Or with h chosen small, say $h=.2$ as illustrated, the system has the properties of a low-pass filter, with high loss for high values of x , and especially high loss near $x=1$. That is, the properties of the filter can be greatly modified by choice of the impedance level parameter. While the use of this central network with $p=s=0$ is known for purposes of making the loss infinite at $x=1$, it is believed new to choose the impedance level as here defined either abnormally high or abnormally low to produce the low pass or high pass effect. For example, in the design of resistance-capacitance filters for ripple elimination in power supplies for radio, it would be new to use a filter of this type with $s=0$ so that the filter will pass direct current, and also with h abnormally small to permit effective passage of direct current, and F_0 chosen at 120 cycles to attenuate especially the double frequency ripple in a full wave rectifier operated from 60 cycle supply.

Application of the filter with s not zero is for band-pass purposes, illustrated in Figure 3. Sharpness of cut-off is greatly enhanced by the fact that the insertion loss must go to infinity at $x=1$. The constants are here chosen to make the insertion loss lowest at a value of x less than unity, and to make the insertion loss for values of x greater than unity always greater than for x yielding minimum loss.

With C_3 finite corresponding to a positive value of s , it is physically apparent that the loss will be infinite both at $x=0$ and $x=1$, therefore with a minimum finite loss at a point between $x=0$ and $x=1$. Also with C_2 finite, corresponding to a positive value of p , it is apparent that the loss will be infinite also at $x=\infty$ and therefore a minimum finite loss also at a point between $x=1$ and $x=\infty$. While of course it is possible to set up the condition to determine the points of minimum loss between $x=0$ and $x=1$, and also between $x=1$ and $x=\infty$, and also to determine the losses at these points of minimum, the equations are so complex that it is quite impracticable. If the design for band-pass purposes is to be by computation, it is much simpler to proceed by the method of trial and error. The two combinations of Figure 3 illustrate designs that have been made for specific purposes. The curve for $h=.2$, $p=0$, $s=.4$ produces a band-pass effect without requiring condenser C_2 . The filter so organized, with F_0 chosen 1000 cycles, is suitable for transmitting well at 120 cycles, and badly at higher frequencies, especially in the range of maximum audibility. The curve $h=1$, $p=.2$, $s=.2$ gives band-pass effect in the vicinity of $x=.2$, with p chosen so that for $h=1$, $s=.2$, the filter also transmits equally well a band of frequencies in the vicinity of $x=4$. Or this arrangement may be considered as a band elimination arrangement for which the loss be-

comes a minimum at points other than $x=0$ or $x=\infty$.

These examples will serve to illustrate some of the three-fold infinitude of curve shapes which may be used as a basis of design with this structural arrangement.

Various modifications may be made in the invention without departing from the spirit and scope thereof, and it is desired therefore, that only such limitations shall be placed thereon as are necessitated by the prior art and set forth in the appended claims.

What I claim is:

1. A resistor-capacitor filter circuit comprising a T-network of series condensers and a shunt resistance, a second T-network connected in parallel to the first having series resistances and shunt condenser, series and shunt condensers connected to the input of said networks, and similar series and shunt condensers connected to the output of said networks.

2. A resistor-capacitor filter network comprising a pair of input and a pair of output terminals, a pair of condensers serially connected across the input terminals, a similar pair of condensers connected across the output terminals, corresponding condensers, one from each pair, having a common terminal which is connected to one of the input terminals and also to one of the output terminals, and a three-terminal network comprising resistors and capacitors having one terminal connected to said common terminal and its other two terminals connected respectively to the common terminals of the serially connected condenser pairs.

3. A resistor-capacitor filter network as defined in claim 2 wherein a frequency source and a terminating resistor are connected between the

input terminals, and a terminating resistor is connected between the output terminals.

4. A resistor-capacitor filter network as defined in claim 2 wherein the three-terminal network comprises a pair of parallel T-networks, one T-network comprising series condensers and a shunt resistor, the other T-network comprising series resistors and a shunt condenser.

5. A resistor-capacitor filter network comprising input and output terminating resistors, a plurality of condensers of values C_3 , C_1 , C_1 and C_3 series-connected between said resistors, a pair of resistors of equal value R_1 connected in shunt to the condensers of equal value C_1 , a condenser of value $2C_1$ having one terminal connected to the common terminal between the resistors of equal value R_1 , a condenser of value C_2 connected to each of the other terminals of the resistors of equal value R_1 , and a resistor of value

20

$$\frac{R_1}{2}$$

having one terminal connected to the common terminal of the condensers of equal value C_1 .

6. A resistor-capacitor network as defined in claim 5 wherein the values of the several condensers and resistors are so chosen that there is produced a very high insertion loss for one frequency and a minimum of insertion loss at another finite frequency other than zero.

7. A resistor-capacitor network as defined in claim 5 wherein the values of the several condensers and resistors are so chosen that the network serves as a low pass or as a high pass filter in accordance with the choice of the impedance level of the filter elements with respect to the terminating resistors.
